UNITED STATES PATENT OFFICE.

ANDREW G. ANDERSON, OF QUINCY, MASSACHUSETTS, ASSIGNOR TO CARR FASTENER COMPANY, OF CAMBRIDGE, MASSACHUSETTS, A CORPORATION OF MAINE.

FASTENER.

Application filed January 22, 1924. Serial No. 687,728.

This invention aims to provide an improved fastener.

Referring to the drawings, which show one illustrative embodiment of my invention:

Figure 1 is a front elevation of a preferred form of fastener;

Fig. 2 is a front elevation of the stud;

Fig. 3 is a section on the line 3—3 of Fig. 1;

Fig. 4 is a section on the line 4—4 of Fig. 1, being partly in elevation and showing the socket withdrawn from the stud; and

Fig. 5 is a section on the line 5—5 of Fig. 4.

In the preferred form of my invention selected for illustrative purposes, I have shown a socket attached to a curtain 5 by 20 prongs 7 struck up from a back plate 9, which pass through the curtain to engage and be clenched by a front plate 11. The back plate 9 presents a stud-receiving aperture 13 having a continuous peripheral wall 25 14, which is resiliently pressed by the neck of the stud when the stud and socket are engaged. This wall is preferably, as illustrated, substantially thicker than the metal of which the back plate is formed, thereby 30 to provide a substantial bearing surface.

The stud includes a neck 15 and a head 17 struck up from a plate 19, the head made unsymmetrically contractile and expansible by slots 21, 21, extending to the base of the stud and preferably, as illustrated, extending sufficiently into the base so that a line between their ends will not pass through any portion of the stud which projects from the base. The stud illustrated is also rendered 40 slightly contractile and expansible laterally by the provision of a third slot 27, connected to the slots 21, 21 at the outer end of the stud, but extending a substantially less distance toward the base, preferably not extending to the neck portion of the stud and terminating, as illustrated, adjacent the edge of the outer face of the stud.

The stud illustrated thus provides two parts, an upper, or semi-rigid part 23, slightly collapsible laterally, and a bottom resilient portion 20, the latter preferably as above described adapted to flex about a flat portion of the base lying between the ends of the slots 21, 21. As viewed in Fig. 2, the so-called upper part 23 includes all of the

projecting portion of the stud between the two slots 21, 21 in which the slot 27 is provided; and the so-called bottom portion 20 includes the remaining projecting portion of the stud between the slots 21, 21 or the small portion of the stud. The projecting portion of the stud is preferably substantially round in cross-section at the head, and at the neck, but the circle provided by the head is preferably eccentric relative to the circle provided by the neck, the eccentricity of the head relative to the neck being away from that side of the stud which provides the resilient portion 21. Thus in the preferred form of my invention illustrated, there is provided a substantial shoulder 25 at that side of the stud opposite the resilient portion 21, this shoulder gradually growing less at the sides of the stud and substantially disappearing at that side of the stud presenting the resilient portion 21.

When the stud and socket are engaged, they are locked against separation by any strain other than a separating pull at the side presenting the resilient portion of the stud because the upper part 23 of the head is not resilient enough to permit the wall of the aperture 13 to pass over the shoulder 25, and because any reasonable outward strain at either side of the stud at or above the center thereof cannot produce sufficient contraction of the stud to permit the socket or eyelet to pass over the head of the stud. Thus I have provided a three-side lock fastener which is locked against separation by a pull adjacent the three sides of the stud at which the shoulder 25 is provided, because, as before stated, the upper part cannot easily be contracted. The stud and socket may, however, be separated by a slight manual pull exerted outwardly upon the curtain at that side adjacent the resilient portion 20 of the stud. This action contracts the stud by pressing inwardly the member 20, which, preferably as illustrated, presents a surface curving gently outwardly and upwardly from the neck of the stud, thus providing a camming surface allowing disengagement of the socket from the stud by a tipping action. In a co-pending application, filed herewith, I have shown a somewhat similar construction wherein the stud, instead of the socket, is mounted on the curtain. The claims of the present application are either generic to both forms

105

110

or specific to the form herein illustrated, while my co-pending application emphasizes those points of advantage inherent to the form of my invention therein disclosed.

5 While I have shown and described a preferred form of my invention, it will be understood that changes involving omission, substitution, reversal and alteration of parts, and even changes in the mode of operation, 10 may be made without departing from the scope of my invention, which is best defined in the following claims.

Claims:—

15 1. A stud and socket fastener comprising, in combination, a socket presenting a stud-receiving aperture, a stud having a head and a neck, said head being of substantially the same contour as the wall surrounding the stud-receiving aperture thereby to permit engagement of said stud with said socket by direct axial movement of one toward the other, a relatively short slot formed entirely in the outer end of said head to provide a semi-rigid portion, a shoulder located 25 upon said semi-rigid portion between said head and said neck to prevent separation of said stud from said socket by relative tipping movement between said stud and socket at that side of said stud and a resilient portion 30 located opposite one end of said slot.

2. A stud and socket fastener comprising, in combination, a socket presenting a stud-receiving aperture, a stud having a head and a neck, a relatively short slot located 35 entirely in the upper end of said head to permit slight contraction of the upper portion of said head, a continuous shoulder located upon said upper portion between said head and said neck to prevent separation 40 of said stud from said socket by relative tipping movement between said stud and said socket at three sides of said stud, and a plurality of generally radially disposed slots connected with said first named slot, said 45 slots extending to the base of the stud to provide a contractile and expansible part at the bottom of said stud whereby to permit separation of said stud from the socket by relative tipping movement between said stud 50 and socket when a pull is exerted adjacent the bottom of the stud.

3. A stud for separable fasteners comprising a head, a neck, a shoulder partly surrounding said stud between said head and neck, and a base, said head having a short

radial slot in the face thereof to provide a semi-rigid portion and a plurality of radial slots extending from said short slot into said base of said stud to provide a resilient portion on the opposite side of the stud 60 from said semi-rigid portion.

4. A stud for separable fasteners comprising a head and a neck, said head having a substantially rigid upper portion, a radial slit located entirely within the extreme outer 65 face of said stud head and a separate contractile and expansible lower portion of substantial width resiliently connected to the base of the stud and independent of the upper portion for substantial yieldable engagement with a socket.

5. A stud for three-side lock fasteners including a head, a neck and a base portion, said head and neck divided by a single relatively short slot located entirely in the head 75 of the stud and a plurality of longer slots diverging from one end of said short slot to provide a semi-rigid portion and a resilient portion, the semi-rigid portion providing the top and sides of the stud and the resilient portion providing the bottom of the stud, the slots providing said resilient portion extending from the head a substantial distance into said base to permit said resilient portion to yield at the junction thereof 80 between the neck and the base of the stud, said head being eccentric relative to said neck to provide a shoulder on said semi-rigid portion between said head and said neck, said shoulder being substantially less 85 pronounced at the sides than at the top of said stud.

6. A stud for a three-side lock fastener comprising a head, a neck and a base portion, said head and neck being divided by a 95 plurality of slits into a substantially inflexible shoulder portion for locking said stud with the socket against separation at at least one side thereof and a freely contractile and expansible portion to permit separation 100 of the stud from the socket by a pull adjacent the contractile and expansible portion, at least two of said slits intersecting in the head and terminating at points below a horizontal plane passing through the center of the stud.

In testimony whereof, I have signed my name to this specification.

ANDREW G. ANDERSON.
